(57) CLAIM

The ornamental design for a parallel hybrid three-wheel passenger vehicle with reconfigurable chassis and power systems, as shown.

DESCRIPTION

FIG. 1 is a front view of a parallel hybrid three-wheel passenger vehicle with reconfigurable chassis and power systems showing my new design;

FIG. 2 is an oblique front view thereof;

FIG. 3 is a right side view thereof;

FIG. 4 is a oblique rear left view thereof; and,

FIG. 5 is an oblique front view with open clam-shell canopy thereof.
